PRODUCING LOWER ALKYL ESTERS

Robert Gardner King, Norwalk, and Robert Joshua King, New Canaan, Conn., assignors to The Photo Technical Corporation, Norwalk, Conn., a corporation of Connecticut

No Drawing. Application January 1, 1945,
Serial No. 571,016

8 Claims. (Cl. 260—410.9)

1

This invention relates to improvements in the preparation of the lower alkyl esters of the fatty acids which occur naturally in the form of glycerides.

A number of methods of preparing the lower alkyl esters of the higher fatty acids from the naturally occurring glycerides have been described, including processes involving alcoholysis or re-esterification, carried out by heating the glyceride with the lower alcohol, such as methyl or ethyl alcohol in the presence of a catalyst, usually an alkali catalyst, although acid catalysts have been suggested and used under substantially anhydrous conditions. It has been generally considered that the reaction will not proceed in the presence of any substantial amount of water or in the presence of any substantial amount of free fatty acid in the fat or oil. In the procedures heretofore used, therefore, it has been necessary to use substantially anhydrous alcohol, and to use refined fats or oils, substantially free from water and with a low free fatty acid content or, in the case of oils or fats with relatively high fatty acid content, to take special precautions, such as the conversion thereof to soap, prior to carrying out the alcoholysis reaction. With alkali catalysts, anhydrous conditions, and the substantial absence of free fatty acid, high yields of the lower alkyl esters of primary alcohols can be obtained, and the glycerine can be substantially recovered in fairly concentrated form. However, the process is industrially difficult, as it is difficult to maintain substantially anhydrous conditions, and it is expensive to so refine the oil as to reduce its free fatty acid content sufficiently or, if compensation is made for the presence of the free fatty acid by the addition of a saponifying agent, difficulties are encountered in separating the glycerine from the alkyl esters which are formed, possibly because of the emulsifying action of the soap. The esters of secondary alcohols, e. g., isopropyl, are produced with even greater difficulty and with very poor yields. Yields with acid catalysts, by methods heretofore proposed, are not good with both primary and secondary alcohols.

The lower alkyl esters have a number of industrial applications as such, and are conveniently used for the production of soap by saponification.

The present invention provides an improved process for the alcoholysis or re-esterification of the glycerides to produce the lower alkyl ester of the fatty acids, and particularly the methyl

2

esters. The process proceeds efficiently even though the oil or fat contains a substantial proportion of free fatty acid, and makes unnecessary removing the free fatty acids or converting them to soap with consequent difficulties in separating the liberated glycerine. The alcoholysis or re-esterification proceeds to substantial completion and the separation of the glycerine formed from the alkyl esters formed is rapid and substantially complete.

In accordance with the present invention, the lower alkyl esters of the fatty acids of the fats or oils as they naturally occur are prepared by the alcoholysis or re-esterification of the glyceride with a lower alcohol, advantageously in the presence of a substantial quantity of water, with the use of an acid, usually sulfuric acid, and an acid-compatible emulsifying agent, advantageously mahogany acids. The reaction proceeds

readily at relatively low temperatures, and ordinarily is carried out at reflux temperatures and with thorough agitation. When the reaction has proceeded to substantial completeness, the reaction mixture is subjected to stratification.

A lower layer, which contains the glycerine, acid, water and excess alcohol readily separates, and may be treated for the recovery of the glycerine and the excess alcohol. The upper oily layer consists of the lower alkyl esters of the fatty acids. Conversions ranging as high as 93 per cent or higher, are obtained. Free fatty acid in the fat or oil used is converted to the lower alkyl ester in the course of the reaction, so that the alkyl esters produced will contain but a very small amount of free fatty acid, even though the original fat or oil contains a substantial proportion of free fatty acid. Most of the impurities present in the original fat or oil will separate into the lower layer.

The glycerine is readily recovered by neutralizing the lower layer with solid soda ash or other alkali, filtering off the inorganic salts formed, and distilling the excess alcohol and water from the filtrate. If necessary, the glycerine may be distilled, although, in many cases, such distillation to produce a commercially acceptable glycerine is unnecessary.

The lower alkyl esters produced, which may be quite pure, if prepared from high grade fats or oils, may be used as such for industrial purposes or saponified in one of the usual ways to produce soap. If the esters are prepared from relatively impure fats or oils, they may contain sufficient impurity to make their use as pro-

duced impractical, whether the use is of the esters as such or for the production of soap. In such case, the esters may be distilled under a relatively high vacuum, advantageously with the use of steam. These esters, particularly the methyl and ethyl esters, distill at lower temperatures than the free fatty acids do, and the distillation does not involve the formation of pitch or tar to the extent that the distillation of fatty acids does. At least a portion of the mahogany acid or other agent, such as toluene sulfonic acid, remains in the ester layer, and the esters may be rapidly and completely split through the action of this agent by the addition of dilute acid and carrying out the hydrolysis under conditions such that the alcohol, as formed, is distilled off.

The invention will be illustrated by the following specific examples, but it is not limited thereto.

Example I

One thousand parts of tallow having an acid value of about 5 are melted and added to a solution or mixture containing 25 parts of water, 67 parts of 95% sulfuric acid, 330 parts of commercial methyl alcohol and 30 parts of mahogany acid. The mixture is heated to refluxing temperature for 12 hours with agitation. The heat is then shut off and the mixture allowed to remain quiescent until it separates into two clean layers. The lower layer, containing the glycerine, water and methyl alcohol, is separated from the oily layer, consisting of the methyl esters of the tallow fatty acid. Conversion to the methyl esters was in one case 97% of theoretical. The glycerine-containing layer may be treated to recover the glycerin by any suitable procedure, such as by treating the lower layer, after separation from the oily layer, with soda ash until neutral, filtering off the sodium sulfate, and distilling off the methyl alcohol and water. The crude glycerine so obtained may be further purified by vacuum distillation. The oily layer, consisting of the methyl esters of the tallow fatty acids, is washed with water or an aqueous solution of salt to facilitate the separation of the glycerine, and to remove such impurities as may be removed by this washing. If, in this procedure, tallow fatty acids are used in place of tallow a high yield of the same methyl esters is obtained, but, of course, no glycerine is obtained as a by-product.

Example II

One thousand parts of tallow are melted and added to a solution or mixture containing 100 parts sulfuric acid, 650 parts of 91% isopropyl alcohol and 20 parts of mahogany acids. The mixture is refluxed for 12 hours with agitation. The heat is then shut off and the mixture allowed to settle, whereupon it separates into a lower layer and a floating oily layer consisting of about 95% isopropyl esters of the tallow fatty acids, which latter layer may be washed with water or an aqueous salt solution to facilitate the settling and separation.

Advantageously, the quantity of water present in the reaction mixture in the practice of the present invention is substantial, although anhydrous or substantially anhydrous conditions may be used. It may range as high as 50% of the total mixture of water and alcohol, or even higher, e. g., up to 90% or somewhat more. Ordinarily, to reduce the reaction volume as much as is feasible, such large quantities of water as 50% will not be used, but smaller quantities,

such as 10 to 20%, based on the alcohol, will be used. One of the advantages of the presence of water in the reaction mixture is that it permits the use of sulfuric acid as a catalytic agent without incurring risk of side reactions, such as the formation of ethers, charring, or the like, which results from the use of concentrated sulfuric acid.

Instead of sulfuric acid, other acids, such as hydrochloric acid or phosphoric acid, or acid salts, such as acid sodium sulfate, may be used, but because of its economy, sulfuric acid is the acid of choice.

One of the indications of the efficiency of the process of the present invention is that even secondary alcohol, such as the isopropyl alcohol of Example II, may be used in the re-esterification reaction with high efficiency. Most of the processes heretofore proposed have not been workable with secondary alcohols, such as isopropyl alcohol, at least in the sense that substantial conversion of the glyceride to the alkyl ester has not been obtainable. Any of the lower alcohols, including methyl, ethyl, iso and normal propyl, butyl and amyl alcohols may be used in the practice of the invention. Tertiary alcohols, such as tertiary butyl alcohol, may also be used, as may mixtures of alcohols, to produce mixed esters.

While the use of the mahogany acids is of marked advantage, as compared with other acid-compatible emulsifying agents, in promoting the efficiency and completeness of the re-esterification reaction, other agents such as toluene sulfonic acid, naphthalene or alkyl naphthalene sulfonic acids, etc., in general, the acid-compatible emulsifying agents, promote the efficiency and completeness of the reaction.

The invention is applicable to the production of the lower alkyl esters of any of the naturally occurring fatty acids, and in particular, to the re-esterification or alcoholysis of any of the natural fats or oils, including tallow, coconut oil, olive oil, palm oil, sardine oil, castor oil, whale oil, linseed oil, cocoa butter, etc. It may also be applied to the esterification of the free acids with the alcohol or alcohols, similar conditions being used.

We claim:

1. The process of producing lower alkyl esters of higher fatty acids which comprises reacting a material of the class consisting of higher fatty acid glycerides and higher fatty acids with a lower alcohol in the presence of a mineral acid, an acid-compatible emulsifying agent and water.

2. The process of producing lower alkyl esters of higher fatty acids which comprises reacting a material of the class consisting of higher fatty acid glycerides and higher fatty acids with an aqueous lower alcohol in the presence of a mineral acid and a sulfonic acid emulsifying agent.

3. The process as in claim 1 in which the acid is sulfuric acid.

4. The process as in claim 1 in which the agent is mahogany acid.

5. The process as in claim 2 in which the acid is sulfuric acid.

6. The process as in claim 2 in which the agent is mahogany acid.

7. The process of producing lower alkyl esters of higher fatty acids by re-esterification or alcoholysis of higher fatty acid glycerides which comprises reacting a higher fatty acid glyceride with an aqueous lower alcohol in the presence of sulfuric acid and mahogany acids, the quantity

of water in the reaction mixture being at least 10%, based on the lower alcohol.

8. The process of producing lower alkyl esters of higher fatty acids which comprises reacting a material of the class consisting of higher fatty acid glycerides and higher fatty acids with a lower alcohol in the presence of a mineral acid, an acid-compatible emulsifying agent and water, separating the ester layer from the aqueous layer and hydrolysing it while distilling off liberated 10 alcohol.
